UNITED STATES PATENT OFFICE.

ALEXANDER CRUICKSHANK SCOTT, OF CARDIFF, WALES, ASSIGNOR TO MEXCO LIMITED, OF LONDON, ENGLAND, A BRITISH COMPANY.

EXPLOSIVE.

Application filed August 26, 1924. Serial No. 734,219.

To all whom it may concern:

Be it known that I, ALEXANDER CRUICKSHANK SCOTT, British subject, engineer, residing at Cardiff, in Wales, have invented 5 certain new and useful Improvements in Explosives, of which the following is a specification.

This invention consists of improvements in or relating to explosives, the object being 10 to provide an effective explosive of the Sprengel type, free from the disadvantages that have occurred in the use of explosives of that type. The explosive is mainly intended for use in mines, quarries, railway work, 15 tunnelling and the like.

Cartridges of the Sprengel type have hitherto been made up with a porous cartridge packed with chlorate or other oxygen-carrying crystals being intended to be 20 rendered active only shortly before use by pouring over them a proper quantity of some hydrocarbon such as nitro-benzol or dipping them therein, the hydrocarbon soaking into the body of the cartridge to 25 render it explosive. It has been found that in practical use such cartridges are frequently not homogeneously penetrated by the liquid hydrocarbon employed as fuel. Moreover, in order to render the body of the 30 cartridge as porous as possible and thus facilitate penetration of the fuel, the chlorate is packed only loosely, the specific gravity of the charge in the cartridge in the case of potassium chlorate being usually about 1.3, 35 whereas the density of individual crystals of potassium chlorate is about 2.34. Consequently the amount of explosive in a given space is a minimum, and the intensity of the resultant explosion is not very high.

40 I have found that advantageous results can be secured by packing the crystals closely and providing a charge of which the crystals are not of uniform size but vary sufficiently for the smaller crystals to fill up 45 the spaces between the larger ones so that the density of the charge is raised. In the case of potassium chlorate the density may be raised to as much as 1.9. By using as the fuel a liquid which has the property of 50 creeping or spreading over the surface of the crystals, it is then possible to secure an effective and uniform penetration of the liquid. The intensity of the explosion is increased very considerably both because of 55 the greater density and of the greater uni-

formity of the charge. The closer packing of the crystals affords a fine capillary structure in the body of the cartridge, which assists liquids of the kind referred to penetrate.

60 According to this invention there is provided in or for use in an explosive charge, a cartridge consisting of a porous case and crystals therein of the kind described which are so crushed and packed for the purpose 65 described that the volume of the voids between the crystals does not exceed twenty-two per cent of the total volume occupied by the crystals. To pack the crystals to such a density involves the application of pressure 70 as hereinafter described.

75 Preferably the crystals are ground to a size less than 60 mesh and have at least 30% of crystals of a size less in linear dimensions than 200 mesh. It is found that by grinding to these dimensions the charge can easily be packed to the required density and without the use of an undue amount of pressure such as would burst the porous case.

80 Before the cartridge is used there is introduced a quantity amounting to from 8 to 12% of the weight of the crystals, of a stable mobile liquid hydrocarbon such as 85 paraffin oil (kerosene) which possesses the property of creeping or spreading over the surface of the crystals, forming a very thin film. Sufficient void space must be left between the crystals to accommodate the required quantity of oil. If paraffin oil is 90 employed it must be of a kind which will 95 creep over the crystals. For example, Russian petroleum has been found suitable for the purpose. This oil contains a certain proportion of oils of the series C_nH_{2n} . It is found that paraffin which is free of hydrocarbons other than those of the paraffin series of the type C_nH_{2n+2} does not tend to 100 creep in this way, but it may be rendered suitable for use by the addition of a small proportion of certain hydrocarbons of the benzene ring series containing a plurality of methyl radicles such as xylol $C_6H_4(CH_3)_2$. The proportion of xylol employed may be up to 10% of the weight of hydrocarbon used. Instead of xylol, Persian fuel oil 105 which contains asphaltic compounds may be used.

110 The invention includes a cartridge as above described characterized by the provision of a central axial recess lined with paper (or

- metal, celluloid or the like) which is perforated or otherwise pervious to the liquid hydrocarbon. In this way the capacity of the inner cylinder may be made equal to the 5 volume of hydrocarbon required to be introduced to prepare the cartridge for use, and the hydrocarbon can be introduced into the cartridge by merely filling the central chamber therewith and allowing the liquid to 10 soak into the cartridge. It is preferred, however, to employ a solid cartridge with a case the external walls of which are porous, and to pour the proper proportion of hydrocarbon over the same.
- 15 The invention further includes a method for the manufacture of hollow cartridges as above described which consists in securing together an outer cartridge case closed at one end (preferably made of impervious 20 material) and an inner cylinder co-axial therewith which is perforated or otherwise pervious to liquid, and packing crystals of an oxygen-carrying substance, such as potassium chlorate, into the annular space 25 between the cartridge and the porous inner cylinder by means of an annular feed worm which fits the annular space and is simultaneously oscillated longitudinally and rotated about the axis of the cartridge.
- 30 Preferably the inner cylinder is supported upon a mandrel during the filling operation and the mandrel is removed after the filling operation is completed.

If it is desired to store the chlorate cartridge for some time before the hydrocarbon is added thereto, the cartridge can be wrapped in a layer of waterproof fabric, such as waterproof paper or waterproof linen. The cartridge, after the hydrocarbon has soaked into the powder, may be reintroduced into the waterproof casing, the edges and ends of which are sealed down, say by a suitable glue.

The following is one example of carrying 45 the invention into effect.

Potassium chlorate is either ground or obtained in the form of fine crystals of the mesh already defined. That is to say the crystals will all pass a 60 mesh screen and 50 30% of them will pass 200 mesh. The crystals should be free from moisture. The paper cartridge may be made up of paper perforated with fine holes of a diameter of 0.01-0.04 inches the perforations being so 55 spaced that 50 to 100 perforations occupy 1 square inch.

Alternatively, the cartridge may be made of material of a porous character which must, however, be strong enough to withstand 60 the pressure produced during filling. The cartridge is introduced into a filling machine and the chlorate crystals are firmly packed therein, the density varying from 1.6 to 1.9. The cartridge is then closed at 65 the free end. A convenient diameter for the

cartridge is about one inch, and the length of the cartridge varies according to the charge, a typical example being a cartridge of six inches in length. A known type of filling machine having a helical feeding 70 work can be employed, similar in this respect to that hereinafter described for filling hollow cartridges.

Normally the cartridge is then enclosed in a covering of waterproof paper. The 75 cartridges in this state are non-explosive and can be transported anywhere without the risks attending the transport of ordinary explosives.

When the second stage in the manufacture of the explosive is to be carried out, the cartridge is removed from its waterproof sheath and is placed in a metal trough. The quantity of paraffin oil (kerosene) required for that particular cartridge, 80 and amounting preferably to 10% by weight on the potassium chlorate present, is poured over the cartridge, and the paraffin oil soaks right in. The cartridge is then covered with a sheath of waterproof paper or waterproof 85 fabric as before, the edges and ends being sealed with a suitable glue. Sufficient time must be allowed for the paraffin oil to creep all over the crystals before the cartridge is used; the cartridges are preferably allowed to stand for 24 hours before they are ready 90 for use.

The explosive can be detonated by any usual detonator (such as a No. 6 detonator) 100 which has 15.5 grains of composition containing mercury fulminate.

An alternative method for use where it is desired to employ hollow cartridges is as follows:—

Referring to the accompanying drawing, 105 Figure 1, an outer cartridge or cylinder 10 is preferably made of impervious material, such as waterproof and oilproof paper or fabric. A convenient diameter for the cartridge is about 1 inch, and the length of the 110 cartridge varies according to the charge, a typical example being a cartridge of 6 inches in length. This cartridge is closed at one end as shown at 11, and that end and the edges are secured by a suitable glue. 115 co-axially within this cartridge is secured a cylinder 12 of paper. This paper may be provided with fine perforations and may be wrapped for several turns around a cylindrical mandrel 13, which conveniently has a 120 diameter of one-quarter inch or less, for example the same diameter as the detonator which is subsequently to be introduced therein.

The bottom of the inner cylinder may be 125 glued to the bottom 11 of the outer cylinder. These cylinders are introduced as diagrammatically indicated in the drawing into a filling machine provided with a helical blade or worm 14 which fits between the two cylinders 130

ders. This feeding worm has a shank 15 mounted so that it can be reciprocated longitudinally along its own axis and also rotated. Suitable well known means are provided for effecting such longitudinal reciprocation and simultaneous rotation of the feed worm, which means also allow it to be gradually withdrawn from the cartridge during such movement. The crystals are fed into the 10 cartridge by the funnel 16 and are packed by the feed worm 14 as tightly as possible. An annular disc of water- and oil-proof paper, cut so as to fit tightly inside the cartridge case and having a central hole of the correct 15 size for the tube to pass through, is then pressed down close to the top layer of the salts and is secured to the inside of the cartridge by suitable glue so as to form a water- and oil-tight joint. The mandrel 13 may 20 then be withdrawn.

Alternatively, As shown in Figure 2, the axle of the feeding worm 14 may be provided with a solid cylindrical core or mandrel 17 of slightly less diameter than the 25 core of the hollow worm.

As a further alternative, one end of the perforated tube 12 of the cartridge may be glued or otherwise fastened normally to a disc of paper 18 (Figure 3) which will fit 30 inside the outer tube 10 of the cartridge. Before the filling of the chlorate commences, the perforated tube 12 may be introduced into the hollow axle of the feeding worm 14, the solid core or mandrel 17 (if this is used) 35 fitting inside the perforated tube. The feeding worm 14 is then introduced into the cartridge so that the disc 18 attached to the end of the perforated tube is at the bottom of the cartridge, and the chlorate is then fed 40 and packed (by oscillating and rotating the worm while withdrawing it) into the space between the perforated tube 12 and the outer tube 10 of the cartridge. While the feeding worm is being withdrawn the disc of 45 paper attached to the end of the perforated tube is held down at the bottom of the cartridge by the chlorate crystals which are packed above it, and the tube is left in an axial position after filling is complete. An 50 annular disc of water- and oil-proof paper may then be pressed down close to the top layer of the chlorate, and secured to the inside of the cartridge by suitable glue so as to form a water- and oil-tight joint.

55 At this stage, by whichever method the cartridges have been filled, the free end of the outer cylinder may be folded over and temporarily closed.

When the second stage in the manufacture 60 of the explosive is to be carried out, the end of the outer cartridge is opened out. The quantity of paraffin oil (kerosene) required for that particular cartridge and amounting preferably to 10% of the chlorate present, is 65 poured into the central cavity, and the

paraffin oil soaks right into the cartridge. The outer cartridge is then closed down and it may be sealed with a suitable glue. The perforations in the inner cylinder may be varied in size or number along the length 70 of the inner cylinder in such a manner as to ensure uniform distribution of the paraffin oil in the cartridge.

A measure of the "volume of the voids" in any given cartridge can be obtained by 75 comparing the weight of the cartridge as a whole with the weight which it would have, calculated on the assumption that the space was completely filled with a substance of the same density as the substance of the 80 crystals. Thus the density of potassium chlorate crystals is 2.34. If the density of the space in the cartridge which is packed with potassium chlorate crystals be equal to 1.9 then, the volume of the voids will be 85 equal to

$$\frac{2.34 - 1.9}{2.34} = 18.8\%$$

of that space. In the following claims the 90 expression "crystals of the kind described" is intended to be limited to crystals of potassium chlorate, potassium perchlorate, an ammonium perchlorate, or mixtures containing these crystals. 95

What I claim as my invention and desire to secure by Letters Patent is:—

1. A cartridge consisting of a porous case and crystals therein of the kind described which are so crushed and packed for the 100 purpose described that the volume of the voids between the crystals does not exceed thirty-two per cent of the total volume occupied by the crystals and yet is adequate to accommodate the necessary quantity of hydrocarbon. 105

2. A cartridge consisting of a porous case and crystals therein of the kind described which are so crushed and packed for the 110 purpose described that the volume of the voids between the crystals does not exceed nineteen per cent of the total volume occupied by the crystals and yet is adequate to accommodate the necessary quantity of hydrocarbon. 115

3. A cartridge consisting of a porous case packed under pressure with crystals of the kind described ground for the purpose described to a size less than 60 mesh and having at least 30% of crystals of a size less than 200 mesh. 120

4. A cartridge consisting of a porous case and crystals therein of the kind described which are so crushed and packed for the 125 purpose described that the volume of the voids between the crystals does not exceed thirty-two per cent of the total volume occupied by the crystals and into which has been introduced a quantity, amounting to from eight to twelve per cent of the weight of the 130

4
crystals, of a stable mobile liquid hydrocarbon such as paraffin oil (kerosene) of the kind described which possesses the property of creeping or spreading over the surface of the crystals, forming a very thin film.

5. A cartridge consisting of a porous case and crystals therein of the kind described which are so crushed and packed for the purpose described that the volume of the voids between the crystals does not exceed nineteen per cent of the total volume occupied by the crystals and into which has been introduced a quantity, amounting to from eight to twelve per cent of the weight 10 of the crystals, of a stable mobile liquid hydrocarbon such as paraffin oil (kerosene) of the kind described which possesses the property of creeping or spreading over the surface of the crystals, forming a very thin 15 film.

6. A cartridge consisting of a porous case packed under pressure with crystals of the kind described ground for the purpose described to a size less than 60 mesh and having at least 30% of crystals of a size less 20 than 200 mesh and into which has been introduced a quantity, amounting to from eight to twelve per cent of the weight of the crystals, of a stable mobile liquid hydrocarbon such as paraffin oil (kerosene) of the kind described which possesses the property of creeping or spreading over the surface of the crystals, forming a very thin film.

7. A cartridge consisting of a porous case and crystals therein of the kind described which are so crushed and packed for the purpose described that the volume of the voids between the crystals does not exceed thirty-two per cent of the total volume occupied by the crystals and into which has been introduced a hydrocarbon which contains a benzene derivative containing a plurality of methyl radicles.

8. A cartridge consisting of a porous case and crystals therein of the kind described which are so crushed and packed for the purpose described that the volume of the voids between the crystals does not exceed thirty-two per cent of the total volume occupied by the crystals and into which has been introduced a hydrocarbon which contains xylol.

9. A cartridge consisting of a casing and crystals therein of the kind described which are so crushed and packed for the purpose described that the volume of the voids between the crystals does not exceed thirty-two per cent of the total volume occupied by the crystals, the casing being rendered porous by fine perforations in the walls of the casing too small to permit escape of the crystals.

10. A cartridge consisting of a casing and crystals therein of the kind described which are so crushed and packed for the purpose

described that the volume of the voids between the crystals does not exceed nineteen per cent of the total volume occupied by the crystals, the casing being rendered porous by fine perforations in the walls of the 70 casing too small to permit escape of the crystals.

11. A cartridge comprising a casing in the form of an external shell and a central axial tube therein so much smaller than the 75 shell as to leave a space between the shell and the tube, said tube being pervious to liquid hydrocarbon, and crystals between the casing and the tube which are so crushed and packed for the purpose described that the volume of the voids between the crystals does not exceed thirty-two per cent of the total volume occupied by the crystals.

12. A cartridge comprising a casing in 80 the form of an external shell and a central axial tube therein so much smaller than the shell as to leave a space between the shell and the tube, said tube being pervious to liquid hydrocarbon, and crystals between 85 the casing and the tube which are so crushed and packed for the purpose described that the volume of the voids between the crystals does not exceed nineteen per cent of the total volume occupied by the crystals.

13. A cartridge comprising a casing in the form of an external shell and a central axial tube therein between which and the shell is a space, said tube being pervious to liquid hydrocarbon and crystals of the kind 100 described so crushed and packed into said space that the volume of the voids between the crystals does not exceed thirty-two per cent of the volume occupied by the crystals, said tube moreover being of such dimensions that it serves as a measure for introduction of hydrocarbon.

14. A cartridge comprising a casing in the form of an external shell and a central axial tube therein between which and the shell is a space, said tube being pervious to liquid hydrocarbon and crystals of the kind described so crushed and packed into said space that the volume of the voids between the crystals does not exceed thirty-two per cent of the volume occupied by the crystals, said tube moreover being of such dimensions that its internal volume is equal to the volume of hydrocarbon required to be introduced to prepare the cartridge for use.

15. A method for the manufacture of hollow cartridges which consists in securing together an outer cartridge case closed at one end and an inner cylinder co-axial therewith which is pervious to liquid and packing crystals of an oxygen-carrying substance of the kind described into the annular space between the cartridge and the porous inner cylinder by means of an annular feed worm which fits the annular 115 120 125

space and is simultaneously oscillated longitudinally and rotated about the axis of the cartridge.

16. A method for the manufacture of hollow cartridges which consists in securing together an outer cartridge case closed at one end and an inner cylinder co-axial therewith, which is pervious to liquid, supporting the inner cylinder upon a mandrel, and packing crystals of an oxygen-carrying substance of the kind described into the annular space between the cartridge and the porous inner cylinder by means of an annular feed worm which fits the annular space and is simultaneously oscillated longitudinally and rotated about the axis of the cartridge, and subsequently after the filling operation is completed removing said mandrel from the inner cylinder. 15

In testimony whereof I affix my signature. 20

ALEXANDER CRUICKSHANK SCOTT.
